CLAIM

I claim the ornamental design for a hand-held pond vacuum cleaner, as shown and described.

DESCRIPTION

FIG. 1 is a side perspective view of the hand-held pond vacuum cleaner showing my new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is an underside view thereof.
